UNITED STATES PATENT OFFICE.

AXEL EUGEN LUNDBERG, OF SUNDSVALL, SWEDEN.

KITCHEN RANGE.

1,424,660.

Specification of Letters Patent. Patented Aug. 1, 1922.

Application filed December 17, 1921. Serial No. 522,990.

To all whom it may concern:

Be it known that I, AXEL EUGEN LUNDBERG, a subject of the King of Sweden, and resident of Sundsvall, in the Kingdom of Sweden, have invented certain new and useful Improvements in Kitchen Ranges, of which the following is a specification, reference being had therein to the accompanying drawing.

10 The present invention relates to a kitchen-range with the fireplace located over the oven and which is so arranged that the flue-gases are carried off on both sides over the walls of the fireplace and downwards along 15 said walls and the two side-walls of the stove and further under the bottom of the latter to an outlet for the flue-gases. According to the present invention the range is provided with controlling means, through 20 which the range may be so set, that for instance when the range is used for cooking the heat is concentrated under the cooking utensils, and over and around the oven when baking. In order to obtain a draught which 25 is as uniform as possible in all parts of the flues the outlet for the flue-gases under the oven is given a special form, suited for the purpose. For utilizing the heat of the escaping flue-gases the range is 30 combined with a water-heater, which is so arranged, that the flue-gases sweep around it on all sides.

A range according to the present invention is shown in the accompanying drawing, 35 in which Fig. 1 is a vertical section at right angles to the front face of the range. Fig. 2 is a vertical section on the line A—B in Fig. 1 and Fig. 3 is a horizontal section on the line C—D in Fig. 1.

40 The fireplace 2 of the range 1 is located right above the stove 3 and both are so arranged in the range, that a space will be provided everywhere between them and the walls, top and bottom of the range. In 45 the embodiment shown the fireplace is provided with an auxiliary top 4, in which openings 5, 6 are located right under corresponding cooking holes in the top 7 of the range. Said arrangement is done in 50 order to concentrate the fire under the cooking utensils. The flue-gases escape at both sides over the walls of the fireplace and downwards along the sides of said fireplace and the stove and further under the 55 stove 3 to an outlet 30 in the bottom of the

range. A series of openings is provided in the upper part of each one of the side-walls of the fire-place. A downwards inclined screen 9 extends above each one of the walls, said screens being extended all 60 along the fire-place. Dampers 10 are pivotally connected to the free edges of said screens or the screens themselves are made in the form of dampers. The dampers of the one or the other kind may be swung 65 in against the wall of the oven or out against the wall of the range by means of a shaft which extends through the latter wall. In the former case the flue-gases are forced to pass through the openings 5 and 70 6, at which the fire is thrown right up and parted against the bottoms of the cooking utensils. In the latter case the flue-gases are forced to escape from the fire-place 2 through the openings 8, at which they are 75 guided right down against the stove 3 by means of the screens. By the said arrangement it is made possible to concentrate the heat for example when cooking under the top of the range and when baking over and 80 around the stove.

Of the above mentioned openings 5, 6 in the top of the fire-place the latter may be closed by means of a cover 12, when one cooking-opening only is used. The cover 12 85 is hung up in a link 13, made of a flat bar iron or the like, said link being carried through a slot in the cover 14, which covers the cooking-opening. At the top said link is provided with an eye 15, in which the 90 hook can be inserted in order to lift up and remove the covers 12, 14 when this is required. In order to keep the cover 12 in its raised position when the cover 14 remains lowered the link 13 is at the bottom 95 provided with recesses, so that a thin stem 16 is formed, by means of which the link and the cover 12 can be turned in their raised position and the parts of the link which overlap the stem can be supported 100 by the cover 14. Obviously the fireplace opening at the front may also be provided with a cover arranged in the same way. Under the inner portion of the grate 17, which in the embodiment shown consists 105 of a grating 18, is provided a slideable damper in the form of a corresponding grating 19, by means of which the openings in the grate can be closed. Said damper is moved by means of a bar 20, which passes 110

through the fore wall of the range. When the opening 6 is closed this damper is kept shut, whereby the combustion takes place only in the fore portion of the fireplace. The chamber 21, located under the bottom of the range is provided with two outlets 23, 24 for the flue-gases of which the former leads directly to the flue in the masonry of the range and the latter to a chamber 25 at the side of the range, which chamber communicates with the flue in the range-masonry through a passage leading from the opening 26 in the upper portion of one of the side-walls of the latter. A water-heater is provided in the chamber 25 in such a way that the flue-gases sweep around it on all sides. The hot water from said heater may be used for different purposes. The chamber 21 is partitioned by means of a wall 22, running along the opening 7, which extends to the same level as the inner edge of the opening 24. Through a turnable damper 28, which is operated from the outside, the flue-gases may be led by means of the wall 22 either to the outlet 23 or to the chamber 25, in the latter case for heating the element 27. In the drawing the damper is shown with full lines set for the latter purpose and with dash-lines set in the opposite direction. The wall 22 obviously brings about a reduction of the draught at the rear portion of the chamber 21. In order to make the draught as uniform as possible in all portions of the flues in the range the edges of the opening 30 diverge backwards at an angle suited for the purpose.

Having now described my invention, what I claim as new and desire to secure by Letters Patent is:

1. Kitchen range, provided with a fireplace, located over the stove and which is so arranged that the flue-gases are carried off at both sides over the walls of the fireplace and downwards along said walls and the two side-walls of the stove and further under the bottom of the latter to an outlet for the flue-gases located at the latter place, characterized thereby that one or more openings (8) are arranged in the upper portion of each one of the side-walls, above which openings adjustable screens or stationary screens provided with dampers (10) extend from said walls, by means of which screens the room located on the sides of the fireplace can be screened off in such a way, that the flue-gases either are forced to flow over the walls of the fire-place up against the top of the range or through the openings (8) in the walls of the fire-place right down over and around the oven, in order to obtain a more advantageous concentration of the heat.

2. Kitchen range according to claim 1,

characterized thereby, that the fire-place is provided with an auxiliary top at a suitable depth under the top of the range, said auxiliary top being provided with openings (5, 6), which can be closed and which correspond to the cooking openings, in order to concentrate the fire under the cooking utensils, of which openings the one which corresponds to a cooking hole not being used is kept closed.

3. Kitchen range according to claim 2, characterized thereby, that the top of the fire-place is provided with two openings, of which one is located behind the other and one of which (or both as the case may be) is provided with a cover (12), in which a link (13) extending through a slot in the cover for the cooking opening is fixed, the free end of said link being provided with an eye (15) which serves as a hold for the hook and the stem of which is provided with projections or the like, which when the cover is lifted can be passed through the slot in the cover for the cooking opening and which after the link and corresponding cover are turned around and retain the latter in its raised position.

4. Kitchen range according to claims 2 and 3, characterized thereby that a slideable damper is provided along the grate, by means of which that portion of the grate, located under the fireplace opening which is closed for the time being can be shut, in order to restrict the combustion to the corresponding portion of the fire-place.

5. Kitchen range according to claim 1, characterized thereby, that it is combined with a water-heater, which is so arranged in a chamber, located at the side of the range and connected with the flues, that the flue-gases can sweep around said water-heater on all sides.

6. Kitchen range according to claim 5, characterized thereby that the chamber in which the water-heater is located is connected with the flues in such a way that it can be shut off.

7. Kitchen range according to claim 1, characterized thereby, that the outlet for the flue-gases under the stove has the form of an oblong or elliptical opening, extending in the longitudinal direction of the stove, the sides of said opening diverging against the back of the range in order that the draught shall be as uniform as possible in all portions of the flues in the range, notwithstanding the fact that on account of a damper-arrangement combined with the waterheater and located under the bottom of the range the draught increases towards the forward end of the opening.

In witness whereof, I have hereunto signed my name.

AXEL EUGEN LUNDBERG.
